DESIGN FOR A PIN CLIP

Alfred Philippe, New York, N. Y., assignor to Trifari, Krussman & Fishel, Inc., New York,
N. Y.

Application January 28, 1938, Serial No. 74,666

Term of patent 3½ years

To whom it may concern:

Be it known that I, Alfred Philippe, a citizen of the United States, residing at New York, in the county and State of New York, have invented a new, original, and ornamental Design for a Pin Clip, of which the following is a specification, reference being had to the accompanying drawing, forming part thereof, wherein—

Fig. 2 is a side elevational view of a pin clip showing my new design.

While I have shown my design embodied in a pin clip, it is contemplated that the same may be embodied in similar articles of jewelry without departing from the spirit of my invention.

I claim:

The ornamental design for a pin clip substantially as shown and described.

ALFRED PHILIPPE.
